US0D1072946S

(12) **United States Design Patent** (10) **Patent No.:** **US D1,072,946 S**
(45) **Date of Patent:** **** Apr. 29, 2025**

(54) **ELECTRONIC TABLE GAME**

(71) Applicant: **Aristocrat Technologies, Inc.**, Las Vegas, NV (US)
(72) Inventors: **Timothy Barbour**, Nolensville, TN (US); **Paul Barker**, Chicago, IL (US); **Rajendrasinh Jadeja**, Las Vegas, NV (US)

(73) Assignee: **Aristocrat Technologies, Inc.**, Las Vegas, NV (US)

(**) Term: **15 Years**

(21) Appl. No.: **29/869,260**

(22) Filed: **Dec. 27, 2022**

(51) **LOC (15) Cl.** **21-03**

(52) **U.S. Cl.**

USPC **D21/369**

(57) **CLAIM**

The ornamental design for an electronic table game, as shown and described.

DESCRIPTION

FIG. 1 is a perspective view of an electronic table game, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In these drawings, solid lines illustrate the claimed ornamental design, whereas broken lines illustrate unclaimed environmental features and form no part of the claimed design.

1 Claim, 7 Drawing Sheets
